UNITED STATES PATENT OFFICE

2,425,378

SUDS-LOCK DECREASING MEANS FOR
SPINNER TYPE CLOTHES WASHING
MACHINES

Charles A. Lindemann, Bridgeport, Conn., assignor to General Electric Company, a corporation of New York

Application April 21, 1943, Serial No. 483,883

2 Claims. (Cl. 68—23)

1

The present invention relates to washing machines of the type in which clothes are washed and centrifugally dried in a spinner basket and is particularly concerned with an arrangement for supplying liquid to the machine to effect the elimination of the friction drag due to soap suds during centrifugal drying.

The object of my invention is to provide an improved construction and arrangement for supplying liquid to a centrifugal extractor type washing machine to effect the killing of soapsuds which may be in contact with the spinner basket and which, if not broken, would exert a drag on the spinner basket, and for a consideration of what I believe novel and my invention, attention is directed to the following description and the claims appended thereto.

In the accompanying drawing, the single figure is a sectional elevation of a washing machine embodying my invention.

Referring to the drawing there is shown a washing machine having a skirt 1 supporting an outer casing comprising lower and upper sections 2 and 3, the lower section resting on a rubber bead 4 at the upper edge of the skirt and being telescoped within the skirt, and the upper section resting on a rubber bead 5 at the upper edge of the lower section and being telescoped within the lower section. In the upper part of the casing is a spinner basket 6 having outwardly flaring side walls provided at the region of greatest diameter with centrifugal discharge openings 7 which during washing serve as overflow openings defining the liquid level. Through suitable mechanism, contained in a casing 8, a shaft 9 extending up through a sleeve 10 sealed to the bottom wall of the lower casing section is selectively oscillated to oscillate an agitator 11 for washing or rotated to rotate the spinner basket 6 for centrifugal drying.

Water is supplied to the machine through a conduit 12 connected to a suitable water supply and having a discharge nozzle 13 in the upper part of the outer casing discharging downward in the space between the spinner basket and the outer casing. The water supply is controlled by a valve 14 which is opened by a suitable means (not shown). During the supplying of water to the machine (and also during washing), a pump 15 is operated to draw water from the bottom

2

of the outer casing through an inlet conduit 16 and discharge the same through a valve 17 and a nozzle 18 into the spinner basket. The valve 17 is a two-way valve which alternatively may be positioned to direct the pump discharge through a conduit 19 to a suitable drain.

The stream of water discharged from the nozzle 18 falls against an annular flange 20 extending inward from the lower edge of the upper casing section 3 which causes the stream to fan out in a spray against the side walls and beneath the bottom of the spinner basket. At, or shortly before, the start of centrifugal drying, when the lower part of the outer casing may be filled with soapsuds to a level above the bottom of the spinner basket, the spray is effective in breaking the soapsuds in contact with the basket which would otherwise exert a friction drag keeping the basket from reaching its centrifugal drying speed. The overcoming of the friction drag of soapsuds (known as "suds lock") is one of the problems arising during the use of this type of machine with excessive soap.

The amount of water supplied to the machine 25 for washing should be sufficient to fill the spinner basket to overflowing so the maximum capacity of the basket will be used. The control of the correct amount of water is effected by a float 21 pivoted on a bracket 22 on the bottom wall of 30 the outer casing and cooperating with a plunger 23 to shut the valve 14 when the liquid level rises to a small value. For reliable control it is necessary that the pump 15 run whenever the valve 14 is opened to supply wash water initially to fill 35 the machine for washing and that the capacity of the pump be greater than the flow through the valve so that the float shuts the valve in response to water overflowing the spinner basket when sufficient water has been supplied for washing. It is 40 also desirable that the pump run during washing so as to maintain the liquid level in the basket.

In the use of the machine, by a suitable control (not shown) the valve 14 is opened and the pump 15 is started to pump the water discharged 45 from the nozzle 13 into the spinner basket. After the basket is filled to overflowing, the float 21 shuts the valve 14. The clothes are loaded into the spinner basket and the agitator oscillated for washing. If an excessive amount of soap is used, 50 soapsuds may fill the outer casing to a point

above the bottom wall of the spinner basket. Under these conditions the friction drag of the soapsuds is sufficient to keep the spinner basket from reaching its centrifugal drying speed and during the slow speed rotation the spinner basket acts as a beater still further increasing the quantity of soapsuds. To eliminate this condition, it is only necessary that the soapsuds in contact with the basket be broken as the remainder of the soapsuds will be dispersed as soon as the basket reaches its centrifugal drying speed. In the present construction, at the end of the washing period the valve 14 is opened for a short interval before and closed a short time after the start of centrifugal drying and the stream discharged from the nozzle is spattered against the side walls and bottom of the basket by striking the flange 20. The spattered stream breaks the soapsuds in contact with the basket and permits the basket to reach its centrifugal drying speed. It will be noted that the filling nozzle 13 functions both to supply water for washing and to eliminate suds lock during centrifugal drying.

The water discharged from the spinner basket during centrifugal drying may be pumped through the conduit 19 to a drain or it may be stored in the bottom of the outer casing and used to fill the spinner basket to wash another load of clothes. When the water is stored in the bottom of the outer casing, the float 21 is in a position to shut the valve 14 so it is not possible to supply an excess of water to the machine which might cause the water level in the outer casing during centrifugal drying to rise up to the bottom of the spinner basket and place an excessive load on the driving mechanism.

What I claim as new and desire to secure by Letters Patent of the United States is:

1. In a washing machine, a spinner basket for

receiving clothes to be washed and centrifugally dried, a casing surrounding the basket having storage space below the basket for liquid contents of the basket, an inwardly extending ledge on the casing adjacent the lower end of the basket, and nozzle means for discharging a stream of fresh water downwardly against the ledge, the arrangement being such as to produce a spray at the lower end of the basket to decrease suds-lock.

2. In a washing machine, a spinner basket for receiving clothes to be washed and centrifugally dried, a casing surrounding the basket having storage space below the basket for liquid contents of the basket, a liquid supply conduit having a nozzle directing a stream of fresh water downwardly along the wall of the casing, and a deflector adjacent the bottom of the basket positioned in line with said nozzle, the arrangement being such that said stream strikes the deflector and is sprayed inwardly at the lower end of the basket to decrease suds-lock.

CHARLES A. LINDEMANN.
